UNITED STATES PATENT OFFICE.

CHARLES HENRI CLAUDEL, OF LEVALLOIS-PERRET, FRANCE.

CARBURETER.

1,170,417.

Specification of Letters Patent.

Patented Feb. 1, 1916.

Original application filed February 6, 1912, Serial No. 675,738. Divided and this application filed May 5, 1914. Serial No. 836,572.

To all whom it may concern:

Be it known that I, CHARLES HENRI CLAUDEL, a citizen of the Republic of France, residing at Levallois-Perret, Seine, France, have invented new and useful Improvements in Carbureters for Internal-Combustion Motors, of which the following is a specification.

This invention relates to carbureters of the general character set forth in a prior application for U. S. Letters Patent, (filed February 6, 1912, Serial No. 675,738), of which the present application is a division, the type of carbureter above referred to being characterized by the employment of a nozzle discharging into the suction space and having associated with it a chamber provided at a point of greater suction with a discharge orifice for the mixed air and fuel and at a point of less suction with an inlet orifice for the admission of air, in connection with passages for admitting liquid fuel to the nozzle and to the chamber independently of the admission of air to the latter. In connection with the parts just referred to I employ in the present case certain additional features of construction and arrangement which are hereinafter described in connection with the accompanying drawing, in which:

Figures 1, 2 and 3 are central vertical sections illustrating various constructions embodying my present improvements; and Figs. 4 and 5 illustrate the shape of the outlet and inlet openings of a rotary cock plug shown in Figs. 1, 2 and 3. Fig. 6 shows the same inlet opening as Fig. 5, but with the parts in a different position.

In Fig. 1, *a* indicates a nozzle or jet contained in a suitable casing or conduit *A* and provided at its upper end with an orifice *o* for discharging liquid fuel into the suction space. This nozzle *a* is supplied with the liquid fuel through its lower end, the constant supply level being indicated by the line *L*, and is surrounded by concentric tubes *b* and *c* and by an upright cup *d*, the top of

which extends slightly above the level *L*. This cup is supplied with the liquid fuel through a lateral perforation *o'* in the nozzle *a* and is kept full to the level *L* when the motor is at rest. The tube *c* is located within the cup *d* and terminates at its lower end above the bottom of said cup, while at its upper end it is connected to the outer tube *b*, so that the tubes and cup form an annular chamber *e* surrounding the nozzle *a* and having alternating baffles therein. At the upper portion of this chamber there are one or more outlet orifices *i* adjacent to the nozzle, and at the lower portion of the chamber the outer tube *b* is provided with one or more inlet orifices *i'*, these orifices *i* and *i'* being thus located in regions of greater and less vacuum, respectively. The upper end of the nozzle *a*, containing the discharge orifice *o*, is shown as located within the interior of a rotatable cock plug *g* having its outlet and inlet orifices *f* and *f'* shaped as shown in Figs. 4 and 5, respectively, the interior of the plug *g* constituting a carburation chamber. To the parts above mentioned, which are shown in substantially the same form in my prior application above referred to, I add in the present case a diaphragm *M* extending across the interior of the nozzle *a* below the constant supply level *L*, and above this diaphragm I provide a perforation *n* in the nozzle *a*, whereby the latter is supplied with liquid fuel from the cup *d*. In Fig. 1 this diaphragm *M* is imperforate, so that the orifice *o* is supplied wholly by way of the perforations *o'* and *n*, and when the motor is running at a low speed it is supplied with fuel exclusively or mainly through this orifice *o*, the vacuum behind the plug *g* being very small while the vacuum in its interior is still considerable. At higher speeds, however, or when the plug *g* is open to a greater extent, the suction in the casing *A* causes an air current to pass through the annular chamber *e* from the inlet orifice *i'*, where the suction is less, to the outlet orifice *i* where the suction is greater,

and the air thus drawn through the cup α empties the latter of its liquid contents and in ascending along the nozzle α takes up and sprays the liquid fuel entering at α' , the mixture being discharged at β into the column of air drawn through the casing, as explained in my prior application.

In Fig. 2 an arrangement is shown which is similar to that illustrated in Fig. 1, except that the diaphragm M' is provided with a small perforation m of sufficient size to supply the orifice α at low speeds, while at higher speeds the supply is increased by way of the perforations α' and n . Thus in both cases the effect of the diaphragm is to diminish or retard the flow of liquid fuel to the orifice α , thus rendering the discharge at α more or less independent of variations in the degree of vacuum which exists at the discharge orifice β of the annular chamber e . In Fig. 2, also, I have shown a cage h surrounding the upper portion of the nozzle α and its discharge orifice α and provided adjacent to said orifice with outlet openings I and at its lower end with inlet openings I' . This form of cage is similar to one of the forms shown in my prior application, and serves to diminish the effect of an acceleration of speed on the amount of liquid fuel discharged through the orifice α and thus to prevent an excessive discharge at high speeds, assuring that said orifice furnishes a suitable supply at low speeds.

In Fig. 3 a somewhat similar cage h' is shown, except that the openings represented by i and I' in Fig. 2 are here merged into openings I^2 which serve alternately for the admission of air into the lower end of the cage h' when the motor is running at low speeds and for the discharge of the mixed air and sprayed fuel into the outer suction column when the motor is running with an open throttle. The diaphragm above described, however, whether perforated or otherwise, may be used in connection with various other arrangements of the nozzle and annular chamber, with or without a cage such as h or h' , and any other suitable cock or valve may be substituted for the specific form of cock plug herein shown.

I claim:—

1. A carbureter comprising a nozzle discharging at its upper portion into the suction space, a diaphragm located below the constant supply level and dividing the interior of the nozzle into two parts, means for admitting liquid fuel to said nozzle below the diaphragm, and a chamber associated with the nozzle and provided at a point of less suction with an orifice for the admission of air and at a point of greater suction with a discharge orifice for the mixed air and fuel, said nozzle being provided with an opening located below the diaphragm and

with another opening located above said diaphragm and affording communication between said chamber and the interior of the nozzle. 65

2. A carbureter comprising a nozzle discharging at its upper portion into the suction space, a perforated diaphragm dividing said nozzle into two parts and located below the constant supply level, means for admitting liquid fuel to the lower portion of the nozzle, and a concentric tube associated with the nozzle and forming a chamber having an air inlet and a discharge outlet located respectively in regions of less and greater suction, said nozzle being provided with an opening located below the diaphragm for supplying liquid fuel to said chamber. 70

3. A carbureter comprising a nozzle discharging at its upper portion into the suction space, a diaphragm provided with a perforation and dividing the interior of the nozzle into two parts below the constant supply level, means for admitting fuel to said nozzle below the diaphragm, and a chamber associated with the nozzle and provided at a point of less suction with an orifice for the admission of air and at a point of greater suction with a discharge orifice for the mixed air and fuel, said nozzle being provided with openings located above and below the diaphragm, respectively, and below the constant supply level, whereby the interior of the nozzle is placed in communication with said chamber. 85

4. A carbureter comprising a nozzle discharging at its upper portion into the suction space, a diaphragm located below the constant supply level and dividing the interior of the nozzle into two parts, means for admitting fuel to said nozzle below the diaphragm, a chamber associated with the nozzle and provided at a point of less suction with an orifice for the admission of air and at a point of greater suction with a discharge orifice for the mixed air and fuel, said nozzle being provided with openings located above and below the diaphragm, respectively, and below the constant feed level, whereby the interior of the nozzle is placed in communication with said chamber, and an air-circulating cage surrounding the discharge outlet from the nozzle. 100

5. A carbureter comprising a nozzle discharging at its upper portion into the suction space, a diaphragm located below the constant supply level and dividing the interior of the nozzle into two parts, means for admitting liquid fuel to said nozzle below the diaphragm, a chamber associated with the nozzle and provided at a point of less suction with an orifice for the admission of air and at a point of greater suction with a discharge orifice for the mixed air and fuel, said nozzle being provided with open- 105

ings located above and below the diaphragm, respectively, and below the constant supply level, whereby the interior of the nozzle is placed in communication with said chamber, an air-circulating cage surrounding the upper portion of the nozzle, and a rotary cock plug having a passage in which the discharge opening of the cage is located, the inlet opening of said cage and the discharge

orifice of said chamber being located behind 10 the cock plug.

In testimony whereof, I have hereunto subscribed my name this 7th day of April, 1914.

CHARLES HENRI CLAUDEL.
